UNITED STATES PATENT OFFICE

103,529

DESIGN FOR AN AIRPLANE

Peter J. Dwareski, Long Beach, Calif.

Application November 5, 1936, Serial No. 65,713

Term of patent 7 years

To all whom it may concern:

Be it known that I, Peter J. Dwareski, a citizen of the United States, residing at Long Beach, in the county of Los Angeles and State of California, have invented a new, original, and ornamental Design for an Airplane, of which the following is a specification, reference being had to the accompanying drawing, forming part thereof.

Figure 1 is a view in side elevation of an airplane showing my new design;

Fig. 2 is a view in front elevation of the same; Fig. 3 is a top plan view.

The characteristic features of my new design are indicated in full lines in the drawing.

I claim:

The ornamental design for an airplane, substantially as shown and described.

PETER J. DWARESKI.
